POWER-DRIVEN HAMMER

Sam Thompson, Houston, Tex.

Application October 6, 1950, Serial No. 188,728

2 Claims. (Cl. 153—48)

1

This invention relates to a power-driven hammer.

An object of this invention is to provide a power-driven hammer which is adapted for use in metal working, wherein it is often necessary to work in locations not permitting the swinging of an ordinary hand-actuated hammer.

Another object of this invention is to provide a power-driven hammer which is particularly adapted for use in automobile body working and repair shops, wherein it is necessary to raise small indentations found on automobile panels in ordinarily inaccessible locations.

A further object of this invention is to provide a hammer which is particularly adapted for attachment to and actuation by a source of motive power of the type usually found in metal working shops, such as the ordinary drill motors.

A still further object of this invention is to provide a power-driven hammer which is relatively compact and of a size and weight facilitating the grasping of the hammer in the hand for movement to a location where the hammer is to be employed.

A still further object of this invention is to provide a power-driven hammer which is relatively simple in structure and cheap to manufacture.

The above and still further objects and advantages of the invention will become apparent upon consideration of the following detailed description of the invention when taken in conjunction with the accompanying drawings, wherein:

Figure 1 is a side elevational view of the power-driven hammer of the present invention;

Figure 2 is a sectional elevational view of the power-driven hammer shown in Figure 1;

Figure 3 is a sectional view taken along the line 3—3 of Figure 1, showing a hammer-actuating cam in one position of its rotary movement;

Figure 4 is a sectional view taken substantially along the line 4—4 of Figure 1, showing the hammer-actuating cam in another position of its rotary movement; and

Figure 5 is an enlarged fragmentary sectional view showing the actuating cam in engagement with the cam track.

Referring now more particularly to the drawings, wherein like reference numerals have been used throughout the several views to designate like parts, there is shown the power-driven hammer of the present invention, generally designated by the reference numeral 10, which is adapted for attachment to a source of motive power, not shown, by means of a power shaft 11.

2

The hammer 10 embodies a body 12 having a work-engaging face 13. The body 12 is provided with a longitudinally extending bore 14 which has one end terminating in, or passing through, the work-engaging face 13 and has the other end terminating adjacent to and spaced from the opposite face 15 of the body 12. A counterbore 16 is provided in the body 12 and extends from the opposite face 15 thereof toward and terminating in communication with the bore 14.

Positioned contiguous to the exteriorly opening end of the bore 14 is an anvil which is loosely mounted within the bore for movement into engagement with a piece to be worked, the anvil being generally designated by the reference numeral 17 and including an anvil pin 18 and a head 19. The anvil 17 is supported within the bore 14 by means of an exteriorly threaded collar 20 which threadedly engages the bounding wall of the bore 14, the collar being provided with a longitudinally extending bore for the extension therethrough of the pin 18 of the anvil 17.

Positioned within the bore 14 in end-to-end relation with respect to the anvil 17 is a hammer shaft 22 which is mounted for periodic movement into and out of engagement with the head 19 of the anvil 17, to thereby urge the anvil against the piece to be worked and to impart hammering blows thereto.

Bridging the open end of the counterbore 16 and supported against the opposite face 15 of the body 12 is a closure cap 23 which includes a depending, exteriorly threaded sleeve 24 threadedly engaging the counterbore 16. The cap 23 is provided with a centrally disposed circular opening 25 for the extension therethrough of a guide pin 26 which is positioned longitudinally of and within the counterbore 16 and fixedly secured to the adjacent end of the hammer shaft 22.

Positioned interiorly of the counterbore 16 and circumscribed about the guide pin 26 is a coil spring 27 for urging the hammer shaft into its position of movement into engagement with the head 19 of the anvil 17.

Positioned transversely within the body 12 and spaced from one side of the hammer shaft 22 is an actuating shaft 28 which has one end terminating exteriorly of the body 12 and threaded, as designated by the reference numeral 29, for engagement with the power shaft 11, the power shaft being connected to the source of motive power. The actuating shaft 28 is journaled within the bore 30 provided transversely of the body 12. The bore 30 terminates in an enlarged, 35 interiorly threaded counterbore 31 in which is

supported a plug 32 provided with an axially disposed seat 33 for rotatably supporting a cylindrical extension 34 carried by the adjacent end of the actuating shaft 28. The plug 32 is provided with a longitudinally extending opening 35 having one end terminating in communication with the seat 33, the shaft opening 35 providing means for introducing a lubricant into the body for lubricating the hammer shaft 22 and the actuating shaft.

The side face of the hammer shaft 22 contiguous to the actuating shaft 28 is cut away to form a flat surface 36 which is provided with a longitudinally extending cam track 37. Carried by the actuating shaft 28 is a camming element 38 which is engageable in the cam track 37 for periodically urging the hammer shaft 22 out of its position of engagement with the anvil 17 in response to the rotary movement of the actuating shaft 28. To maintain the hammer shaft 22 against rotation, a guide bushing 39 is supported on the actuating shaft 28 and engages the flat surface 36 of the hammer shaft 22.

In actual use, the threaded end 29 of the actuating shaft 28 is connected to the power shaft 11, the latter being connected to a source of motive power. Upon effecting the rotary movement of the actuating shaft 28, the hammer shaft 22 will be urged out of engagement with the anvil against the oppositely acting force provided by the resilient element 27. When the camming element 38 is rotated to a position wherein it is no longer in engagement within the cam track 37, the hammer shaft 22 will be urged back into engagement with the anvil 17 to thereby urge the latter against the piece to be worked with an impacting force. The intensity of the hammering blows will be determined by the type of spring employed for biasing the hammer shaft into engagement with the anvil.

Although only one embodiment of the power-driven hammer of the present invention has been described, it is readily apparent that numerous modifications can be made without departing from the spirit of the invention as set forth in the appended claims.

What I claim is:

1. A hammer adapted for attachment to a source of motive power comprising a body having a work-engaging face, there being a longitudinally extending bore provided in said body having one end terminating in said work-engaging face and having the other end terminating adjacent to and spaced from the opposite face of said body, there being a counterbore extending inwardly from said opposite face of said body in communication with said bore, an anvil positioned contiguous to one end of said bore and loosely mounted therein for movement into engagement with a piece to be worked, a hammer shaft positioned within said bore and mounted therein for periodic movement into and out of engagement with said anvil to thereby urge the latter against the piece to be worked and to impart hammering blows thereto, a closure cap bridging the open end of said counterbore and supported against said opposite face of said body, a guide pin having one end extending through said closure cap into said counterbore and fixedly secured to said hammer shaft, resilient means positioned interiorly of said counterbore and supported on said guide pin for urging said hammer shaft into its position of movement in engagement with said anvil, an actuating shaft positioned transversely within said body and spaced from one side face of said

hammer shaft and having one end terminating exteriorly of said body and provided with means for connection to said source of motive power, said one side face of said hammer shaft being cut away to form a flat surface, there being a longitudinally extending cam track provided within said flat surface, a camming element carried by said shaft and engageable in said cam track for periodically urging said hammer shaft out of its position of engagement with said anvil in response to the rotary movement of said actuating shaft, and a guide bushing supported on said actuating shaft and engaging said flat surface for maintaining said hammer shaft against rotation.

2. A hammer adapted for attachment to a source of motive power comprising a body having a work engaging face, there being a longitudinally extending bore provided in said body having one end terminating in said work engaging face and having the other end terminating adjacent to and spaced from the opposite face of said body, there being a counterbore extending inwardly from said opposite face of said body in communication with said bore, an anvil positioned contiguous to one end of said bore and loosely mounted therein for movement into engagement with the piece to be worked, a hammer shaft positioned within said bore and mounted therein for periodic movement into and out of engagement with said anvil to thereby urge the latter against the piece to be worked and to impart hammering blows thereto, a closure cap bridging the open end of said counterbore and supported against said opposite face of said body, a guide pin having one end extending through said closure cap into said counterbore and fixedly secured to said hammer shaft, a coiled spring composed about said guide pin and bearing against said cap and the adjacent end of said hammer shaft for urging said hammer shaft into its position of movement into engagement with said anvil, an actuating shaft positioned transversely within said body and spaced from one side face of said hammer shaft and having one end terminating exteriorly of said body and provided with means for connection to a source of power, said one side face of said hammer shaft being cut away to form a flat surface, there being a longitudinally extending cam track provided within said flat surface, a camming element carried by said shaft and engageable in said cam track for periodically urging said hammer shaft out of its position of engagement with said anvil in response to the rotary movement of said actuating shaft, means carried by said actuating shaft and engaging said flat surface for maintaining said hammer shaft against rotation, and a lubricating plug carried by said body and in communication with the other end of said actuating shaft and said bore for lubricating said hammer shaft and said actuating shaft.

SAM THOMPSON.
